CLAIM

I claim the ornamental design for a remote control vehicle, as shown and described.

DESCRIPTION

FIG. 1 is a perspective view of a remote control vehicle. FIG. 2 is a side view of the left side of the remote control vehicle of FIG. 1.

FIG. 3 is a side view of the right side of the remote control vehicle of FIG. 1.

FIG. 4 is a top view of the remote control vehicle of FIG. 1. FIG. 5 is a bottom view of the remote control vehicle of FIG. 1.

FIG. 6 is a front view of the remote control vehicle of FIG. 1; and,

FIG. 7 is a rear view of the remote control vehicle of FIG. 1.

The broken lines shown are included for the purpose of illustrating the unclaimed portions of the article and forms no part of the claimed design.
